UNITED STATES PATENT OFFICE.

EDWARD JAMES BEAVER, OF GROTON, CONNECTICUT.

CLOTHESRACK.

1,410,240.

Specification of Letters Patent. Patented Mar. 21, 1922.

Application filed June 28, 1921. Serial No. 481,148.

To all whom it may concern:

Be it known that I, EDWARD J. BEAVER, a citizen of Great Britain, and a subject of the King of Great Britain, residing at Groton, 5 in the county of New London and State of Connecticut, have invented certain new and useful Improvements in a Clothesrack, of which the following is a specification.

My invention relates to clothes racks for 10 drying the clothes supported thereby and particularly to a rack adapted to be attached to an ordinary domestic hot water boiler such as used in kitchens, a wall, beam, or any other convenient support.

15 An object of the invention is to provide a rack of this character in which the clothes supporting elements are at all times engaged with the rack, to effectually prevent accidental dislodgment.

20 Another object is the provision in a rack of the character described, of a novel supporting means for the clothes holding elements.

25 A further object is the provision of a novel rack construction in which shearing strain on the clothes holding elements is eliminated.

With these and such other objects in view as will be apparent from the description, my 30 invention resides in the novel construction, combination and arrangement of parts, hereinafter described and claimed, and illustrated in the accompanying drawings, in which:

35 Fig. 1, is a top plan view of the rack as attached to a boiler, the shell thereof being shown in part section.

Fig. 2, an elevation of same with the clothes holding elements in extended position,

Fig. 3, a top plan of a modified form,

Fig. 4, an elevation of the modification,

Fig. 5, a section through the rack body with a clothes holding element shown extended in dotted lines,

Fig. 6, a perspective of a portion of the rack body, and

Fig. 7, a perspective of the head of a clothes holding element.

50 In the preferred form, as shown in Figs. 1 and 2, 1 indicates the shell of an ordinary domestic boiler. The rack body 2, is made of an arcuate, channeled casting, curved to adapt itself to a boiler shell and applied 55 with the upper and lower portions 3 and 4

abutting the boiler. Integral, laterally extending lugs 5 on the ends of the casting, are perforated to receive attaching bolts 6 engaged with similar lugs 7 on a curved band 8 adapted to encircle the remaining 60 portion of the boiler shell, whereby the rack is detachably clamped on the boiler.

The outer face 9 of the body, is provided at spaced intervals with inverted L shaped slots 10, and communicating slots 11 are 65 formed in the lower rack portion 4, extending substantially to the middle thereof. The uppermost walls of the slots 10 are disposed a predetermined distance below the top of the casting, for a purpose to be described.

70 The clothes holding elements comprise arms 12 corresponding in thickness to the width of the slots, and provided with integral, enlarged, squared heads 13. These 75 arms, in normal inoperative position, are disposed in the slots 11 in a vertical position with the enlarged heads engaging the inner surface of the rack body portion 4. When extended, the arms are raised in the slots 10 and moved to the position shown in dotted lines in Figs. 5 and 6. The arms are 80 then supported by the walls of the upper portion or leg of the slot 10. The spacing of these portions of the slots below the top 85 of the casting as hereinbefore described, provides in effect, flanges 14 which coacting with the upper portion 3 of the casting, engage the heads of the arms as shown in Fig. 5. This construction gives additional strength 90 to the arms 12 as a larger supporting surface is engaged, insuring rigidity to the arms when extended and reducing the shearing strain. The squared heads of the arms engaging the inner surface of the rack portion 3 prevent the arms from rolling in the slots, eliminating the possibility of accidental dislodgment of the arms.

95 In the modified form illustrated in Figs. 3 and 4, the rack 2' is of identical construction with the preferred form with the exception that it is adapted for attachment to a support 1' such as a wall or the like, by means of a brace bar 15 suitably secured to the casting and adapted for detachable engagement with the support 1'. In this form of the invention, it is apparent that the top 100 of the rack may be used as a shelf for holding small articles.

105 While I have described and illustrated 110

certain details which enter into the construction and operation of the invention, I desire it to be understood that I do not intend to limit myself to these, but that any such 5 may be used as will fall within the scope of the invention as claimed.

I claim:—

10 A clothes rack comprising a channeled casting adapted for engagement with a support, the walls of said casting forming upper and lower portions and an outer face, said face being provided with spaced, inverted L shaped slots extending from the outer edge of the bottom portion and terminating with one arm of the L in slightly spaced relation below the outer edge of the top portion and parallel therewith, the bottom portion of the casting being provided 15 with inwardly extending slots adjacent and 20 communicating with the lower ends of said

L shaped slots, rack arms disposed through and movable in said slots, enlarged heads integrally formed on said arms and disposed at the interior of said casting in the channeled portion for supporting said arms in a 25 vertical position when disposed in the slots of the lower portion of the casting, said arms being adapted to be moved into the upper portions of said L shaped slots for support in extended position laterally of the casting, the 30 heads of said arms being so configured as to engage against the upper portion of the casting and against the inner portion of said outer face between the upper edge of said L shaped slots and the upper portion of the 35 casting simultaneously, whereby the heads serve to support said arms and prevent rolling thereof.

In testimony whereof I affix my signature.

EDWARD JAMES BEAVER
